UNITED STATES PATENT OFFICE.

REINHOLD MENSCHEL, OF BERLIN, GERMANY.

PUMP FOR ATOMIZERS.

Application filed November 4, 1927, Serial No. 231,128, and in Germany August 17, 1926.

This invention relates to a portable atomizer for use in rooms and the like; its dimensions are only small so that it can be easily carried about from one place to another place 5 wherever needed or desired. The liquid to be atomized is driven upwardly in the form of a jet or jets, for instance by means of a spray, and the jet or jets may be delivered continually or intermittently, and the change 10 from the one state to the other may be suddenly or gradually. The liquid may be perfumed, if desired, so as to perfume thereby also the air in the respective room.

The invention is illustrated diagrammatically and by way of example on the accompanying drawing, on which Figure 1 is a vertical axial section through an apparatus designed according to this invention, the left hand portion of the basin (8) on the top of 15 the apparatus being broken away for want of space; Figure 2 is a similar section only through the lower part of the apparatus and at right angles to the section shown in Fig. 1, and Figure 3 shows the wiring diagram.

On the drawing, 8 denotes a basin intercepting and collecting liquid particles spouted too far laterally, and 29 denotes a receptacle containing the liquid to be atomized. This receptacle may consist of glass or the like. It is carried by a vertical cylinder 7 and has preferably the sectional shape shown in Fig. 1, that is to say, there extends through it a vertical tubular portion constituting an extension of the cylinder 7. This latter and said extension enclose two pipes 5 and 6, of which 5 extends upwardly beyond the said extension and may bear on its top a spray 31, as shown. The pipe 5 is the 20 delivery pipe for the liquid to be atomized, and the pipe 6 is a suction pipe which is connected at its upper end with a piece of rubber hose 28, the free end of which dips into the liquid contained in the receptacle 29.

The pipes 5 and 6 extend upwardly from a valve casing 24 enclosing two ball-valves 3 and 4, of which 3 is the delivery valve and 4 the suction valve. The ball 4 is retained in its position of rest by a small sieve 39 arranged below it, the arrangement being such that when the ball is in this position, as in Fig. 1, the liquid can pass freely from the pipe 6 down into the chamber 32 below the valve casing 24, but when the liquid enclosed 25 in this chamber is subjected to pressure produced by a piston 2, located in the lowermost

part of the cylinder 7 the ball 4 is pressed against the end of the pipe 6 and closes the same. On the other hand, the valve 3 which up to then had been resting on its seat is 60 lifted off the same and then retained by a small sieve 40 located a little below the entrance to the pipe 5 so that the liquid can be forced upwardly in this pipe and out through the spray 31.

The piston 2 consists of soft iron and can be lifted by a solenoid coil 1 surrounding the lower half of the cylinder 7. When an electric current is flowing through the coil 1 the piston-forming core 2 is lifted and forces the 70 liquid upwardly, as just described. It is obvious that the constructional form shown is so designed that the liquid is alternately sucked into the cylinder chamber 32 through the pipe 6 and forced out of it through the 75 pipe 5. This constructional form operates, thus, intermittently, in correspondence with the switching on and off of the coil 1; this is effected by the following mechanism:

There extends downwardly from the piston 80 2 a rod 25 surrounded with a compressive spring 17 which is compressed when the piston moves upwardly, and pulls the piston down into its former position when the coil 1 is current-less. Below the coiled spring 17 a 85 horizontal flat spring 14 is affixed to the piston rod 25, and this spring which, of course, moves up and down together with the piston rod co-operates with two stationary contact pieces 18, as well as with a so-called bridge-member 13 which, in turn, co-operates 90 with two stationary contact-pieces 21 located above the contact pieces 18. When the spring rises, it leaves these contact pieces whereby the respective part of the circuit (hereinafter described) is broken, and finally the bridge-member 13 is lifted off the contact pieces 21 whereby again a part of the circuit is broken. There is a third pair of contact pieces, viz 15, which co-operate with a flat-contact spring 95 19 affixed to the solenoid core 22 of a solenoid coil 12. This coil is connected at one end by a wire 35 with the coil 1 and at the other end with one of the contacts 15, as well as by a wire 37 with one of the contacts 18. The other contact 18 is connected by a wire 100 34 with the negative pole of the source of current, and a branch 36 of this wire is connected with the other of the contacts 15, all as shown in Fig. 3. The other end of the coil 1 is connected with one of the contacts 21, and the other contact 21 is connected by a wire 110

33 with the positive pole of the source of current.

When the current has been switched on, its path is at first: 33, 21, 13, 21, 1, 35, 12, 15, 5 37, 18, 14, 18, 34. Both solenoid coils become now excited, but the core 22 is lifted by far more quickly than the core 2, because 22 need not overcome such a resistance (the liquid bearing upon it) as the core or piston 2 10 must. Consequently, the contacts 15, 15 are conductively connected by the spring 19, and the path of the current now is: 33, 21, 13, 21, 35, 12, 15, 19, 15, 36. The current continues, thus, to flow through the coil 1, although the 15 contact at 18, 14, 18 has been broken. The contacts at 15, 19, 15 lie in series with the coils 12 and 1, but in parallel with the contacts 18, 14, 18.

When the members 2, 25, and 14 arrive in 20 their highest position, the member 14 lifts the contact bridge 13 off the contact pieces 21 whereby the circuit of both coils is broken. The member or piston-forming core 2 is, therefore, now subjected to the action of the 25 spring 17 which pulls it down, back into its initial position where, finally, the spring 14 effects another closing of the circuit at the contact pieces 18, and so on.

When the level in the receptacle 29 has 30 sunk to or below a certain predetermined limit, the apparatus is stopped automatically by the following device:

A vertical tube 38 extending through, and supported by, the bottom of the basin 8 serves 35 as guide for a rod 30, the upper end 27 of which is connected with a float 9 swimming upon the liquid in the receptacle 29. The lower end of the rod 30 is jointed by a slot and pin connection with one arm of a double- 40 armed lever 11, the other arm of which extends to below the contact-bridge 13 and lifts this bridge off the contact pieces 21 when the level of the liquid in the receptacle 29 has sunk to a certain predetermined depth. It is 45 obvious that the circuit is then interrupted and the apparatus, therefore, ceases to work.

The parts located below the basin 8 are, preferably, surrounded with a wall 26, as shown.

50 I claim:

1. In a portable atomizer for rooms and the like, in combination, a receptacle adapted to receive the liquid to be atomized, a cylinder located below this receptacle, a suction- 55 valve arranged in the upper part of this cylinder and a pipe extending from this valve to said receptacle; a delivery valve also ar-

ranged in the upper part of the cylinder, and a delivery pipe extending from this valve upwards to above the said receptacle; a piston-forming solenoid-core in the lower part of said cylinder, a solenoid coil encompassing the cylinder on an adequate length, a change-over switch inserted into the circuit of this coil, and means for operating this switch automatically to cause to-and-fro movement of said piston-forming core. 60 65

2. In a portable atomizer for rooms and the like, in combination, a receptacle adapted to receive the liquid to be atomized, a cylinder located below this receptacle, a suction-valve arranged in the upper part of this cylinder and a pipe extending from this valve to said receptacle; a delivery valve also arranged in the upper part of the cylinder, and a delivery pipe extending from this valve upwards to above the said receptacle; a piston-forming solenoid-core in the lower part of said cylinder, a solenoid coil encompassing the cylinder on an adequate length, another solenoid coil and a core therein connected in series with the first-mentioned coil; two interrupters, of which one is connected with and operated by said first coil and connected in series with both coils, and the other is connected with and operated by said other coil, both interrupters so arranged as to be opened when the current has been switched on, and a third interrupter connected in parallel with the said first interrupter and so arranged as to be opened when the piston arrives at the end of its delivery path, substantially as set forth. 70 75 80 85 90

3. In a portable atomizer for rooms and the like, in combination, a receptacle adapted to receive the liquid to be atomized, a cylinder located below this receptacle, a suction-valve arranged in the upper part of this cylinder and a pipe extending from this valve to said receptacle; a delivery valve also arranged in the upper part of the cylinder, and a delivery pipe extending from this valve upwards to above the said receptacle; a piston-forming solenoid-core in the lower part of said cylinder, a solenoid coil encompassing the cylinder on an adequate length, a change-over switch inserted into the circuit of this coil; a float located in the said receptacle, an electric change-over switching mechanism, and means for transmitting the movements of said float to this mechanism at the ends of the paths of the said pistons. 95 100 105 110

In testimony whereof I affix my signature.
REINHOLD MENSCHEL.
